BUILDING COVERING MEMBER

Gilbert Snyder, South Bend, Ind., assignor to
 Mastic Asphalt Corporation, South Bend, Ind.,
 a corporation of Indiana

Application November 15, 1937, Serial No. 174,597

11 Claims. (Cl. 20—5)

This invention relates to improvements in building covering members, and particularly to material of this character comprising a panel of rigid composition board of compressed cellulose fibers coated with waterproof material and surfaced to simulate the appearance and texture of a section of a masonry wall.

The use of this type of building covering material has proven successful by reason of its substantially permanent decorative exterior, insulating properties, and other desirable characteristics. However, considerable care must be exercised to insure proper application thereof to a building by reason of certain of its characteristics. Thus, in applying the material, which is commonly nailed to place, with the nail piercing the waterproof outer protective coating, it is essential that the nail head and nail hole be thoroughly sealed to prevent seepage of water about the nail and past the waterproofing material to the composition board. This for the reason that the composition board is highly porous and absorptive, and swells, weakens and deteriorates when wet. Another condition to which members of this character have been subject, is the driving of a nail too deeply into the board which is of substantially laminated compressed fibrous character and contains no binder or like medium to afford homogeneity and strength. Thus a nail driven too deep tends to rupture the board. Still another condition to which such members are subject is the absence of any substantial mechanical or friction bond between the panel and a nail, by reason of the structural character of the composition board which makes effective securing of the member difficult and endangers the seal effected by coating the nail head. Likewise, the character of the composition board requires close spacing of nails to insure solid securing of each panel to the frame.

It is, therefore, the primary object of this invention to provide a building covering member wherein the aforementioned difficulties are eliminated and the product is constructed to minimize possibility of failure.

A further object is to provide a building member of this character provided with pre-formed nail holes.

A further object is to provide a building member of this character having a base of composition board provided with preformed nail holes and saturated with waterproofing material adjacent all surfaces thereof including the walls of said nail holes.

55 A further object is to provide a composition

board product of this character of increased strength and rigidity and with insulating properties substantially unimpaired.

A further object is to provide a building member of this character comprising a surface saturated composition board having preformed nail holes, and a waterproof coating normally sealing the outer ends of said nail holes.

A further object is to provide a building member having preformed nail holes sealed at their outer ends, with means indicating the position of said nail holes.

A further object is to provide a building member of this character which is strong and thoroughly waterproof, which requires fewer nails, and which will effectively grip nails.

Other objects will be apparent from the description and appended claims.

In the drawing:

Fig. 1 is a face view of my improved building member.

Fig. 2 is a fragmentary enlarged sectional view taken on line A—A of Fig. 1.

Fig. 3 is a fragmentary enlarged sectional view similar to Fig. 2 and illustrating the manner of nailing the member.

Fig. 4 is a fragmentary enlarged sectional view of the saturated composition board base with a preformed nail hole.

Fig. 5 is an enlarged fragmentary sectional view similar to Fig. 2 illustrating a modified construction of building member.

Referring to the drawing, the numeral 10 designates a building covering member having marginal ship lap flanges 11 and a coated contoured face provided with longitudinal and transverse narrow elongated depressions 12 arranged to simulate mortar joints and separating surface areas simulating masonry members such as bricks 13.

The member is preferably formed on a base best illustrated in Fig. 4, which constitutes a rigid panel 14 of composition board of compressed cellulose fibers, such as "Celotex" and the like. A plurality of spaced narrow holes 15 are formed in and extend through the board 14 in predetermined relation and arrangement. The entire surface portion of the board is saturated to a comparatively shallow depth with waterproof material such as asphalt 16, said saturant also saturating the board at 17 at the walls of each hole 15. Composition board is of compressed laminated fibrous character whereby it has substantially greater porosity at its edges than at its faces, whereby the transversely extending satu-

rated portions, as at 17 around holes 15 are of greater depth than face portions 16. This effectively reinforces the board at its weakest points, as around ship lap flanges 11, and also 5 serves to form a binder for the laminations of the composition board around each nail hole. The saturant preferably penetrates to only a shallow depth sufficient to provide the improved structural and waterproof characteristics without 10 impairing the insulating properties of the composition board to any material extent.

The preferred composition board above described may be treated and finished to provide any of several well known types of finished product. One such type is illustrated in Fig. 2 where- 15 in a continuous surface layer or coating 18 of asphalt or like waterproof material is applied to one face of the preformed panel; and colored granular material or grit 19 is applied to coating 18. This coating is suitably pressed to provide the depressions 12 therein, and thus achieve the masonry simulation. The depressions are preferably located to coincide with the various holes 15 in the board 14, and the formation 25 thereof tends to force the coating material into the upper ends of holes 15 to a substantial extent at 20, as illustrated in Fig. 2. At the same time the depressions 12 are formed, as by suitable dies, indentations 21 may be formed in coating 18 in registering relation to the holes 15. In applying this type of member to a building, the panel is applied flat against a building 22 as against studding, sheathing, siding or the like, and nails 23 are driven therethrough at holes 30 15 and into the building. The nail heads seat in depressions 12, and are completely protected and concealed by waterproofing material at 24.

Another embodiment of the invention is illustrated in Fig. 5, wherein the preformed partially saturated composition board 14 is likewise coated with a comparatively thin continuous layer 18 of adhesive waterproof material sealing one end of holes 15 at 20 and indented at 21 in registration with each hole 15. In this 45 construction, however, the coating 18 serves to cause thin slab units 25 of brick, stone, asbestos composition or the like to adhere to the base in spaced patterned relation. Nails are adapted to be driven through holes 15 in the spaces between 50 slabs 25 to secure the unit to a building as heretofore described, and the spaces then being filled with mortar or like material (not shown) which conceals the nails and completes the surface.

It will be seen that, with both above described 55 types of construction, the nail pierces the portion 20 of coating 18 in holes 15 and passes through said holes in the member without exposing or contacting an unsaturated portion of the board. The increased depth of penetration 60 of the saturant at areas 17 around holes 15 insures against such contact of the nails with unsaturated portions of the board even when the nail is driven at an angle to hole 15; and also 65 serves as a reinforcement to prevent damage to the board if a nail is driven so deeply as to lodge its head below the upper surface of the base. The nails employed are preferably of slightly greater thickness than the transverse dimension 70 of holes 15 so as to insure a tight fit of the nails with the board, and the saturant 17 around the holes 15 insures a binding or adhesive contact as well as a frictional fit between the nail and board. In addition, the saturation of portion 17 around 75 the nail increases the strength of the board

where it is nailed and insures solid effective anchoring of the unit to the building when nailed. In this way fewer nails are required to secure my improved member solidly to a building than are required to secure a conventional unsaturated 5 member of the same character and size. Furthermore, in the event fewer nails are employed than provided for, the unused nail holes 15 remain permanently and effectively sealed in weatherproof manner by portions 20 of coating 10 18 at the outer ends of said holes, so that the presence of such holes will not detract from the weatherproof character of the building member. The indentations 21 which indicate the locations of such unused nail holes are small and inconspicuous, and these factors coupled with the 15 location of the indentations in depressions 12 does not detract from the general appearance of the members and renders the presence of unused nail holes therein unnoticeable when said 20 members are applied on a building. It will, of course, be understood that one of the prime advantages of this construction is the retention of the insulating value of the base by retaining the major portion thereof unsaturated, while at the 25 same time preventing moisture from entering the unsaturated interior of the body by way of the nail holes. In this connection, it will be noted that the construction is particularly effective with the type of construction shown in Fig. 5 30 30 where the slabs 25 render each building unit quite heavy and nailing of the unit tends to deform the board around the hole and to enlarge the hole by reason of said weight, all of which is avoided by the saturation reinforcement of 35 the base as described. Additionally, the Fig. 5 type of construction contemplates the use of regular mortar between slabs without coating the nail heads, the moisture from the mortar thus being directly accessible at the points of nailing, 40 so that any looseness between nail and member in conventional construction permits the moisture to enter the same, whereas all such dangers are eliminated by the instant construction.

For the purpose of stabilizing the product, the 45 saturating agent employed is preferably an asphalt having a comparatively high melt point and substantially free from volatile solvents, and the coating 18 is formed of like material. In this way all possibility of chemical action between the coating and saturant, such as permeation of coating 18 by solvents which dilute 50 the body thereof or impair the adhesive qualities thereof, is avoided.

Attention is also directed to the fact that, with 55 respect to the feature of the tight sealed fit between the board and nails and the waterproof character of the board around the nail, it is possible to avoid or eliminate use of coating 24 over the nail head in the Fig. 3 type of construction, 60 by using rust proof nails of the same color at their heads as the color or coating 18, usually black. In other words, the construction is so sealed around the nail that protection of the 65 board by such coating is unnecessary, and the color problem for concealment of the nail is all that must be considered.

I claim:

1. A building covering member comprising a 70 rigid composition board having a plurality of small nailing passages extending therethrough at the portion thereof which is exposed to the weather when applied, the portions of said board adjacent all exposed surfaces thereof including the walls of said passages being saturated to a 75

shallow depth with waterproofing material, a continuous layer of waterproof material covering the outer face of said board, and surfacing material adhering to said layer, said layer sealing the outer ends of said passages.

2. A building covering member comprising a rigid composition board having a plurality of nail receiving passages extending therethrough, said board being impregnated to a shallow depth at all exterior surfaces thereof and at the walls of said passages by a waterproofing material, and a continuous masonry simulating coating on one surface of said board sealing said passages, said coating having depressions simulating mortar joints and positioned over said passages.

3. A member as defined in claim 2, including means for indicating the position of each passage.

4. A member as defined in claim 2, wherein said coating is provided with an indentation therein above each passage.

5. A construction member adapted to be secured to a building by means of a nail, comprising a composition board having a preformed nail hole of smaller diameter than said nail extending therethrough, the portion of said board around said nail hole being saturated with waterproof material, and a continuous coat of waterproof material on one face of said board normally sealing one end of said passage and adapted for penetration by said nail, said waterproof material effecting a tight adhesive waterproof engagement with said nail.

6. A member as set forth in claim 5, wherein waterproof material of said coat enters and fills one end of said passage.

7. A member as set forth in claim 5, having surfacing material adhering to said coat in spaced relation to said hole.

8. A construction member comprising a rigid composition board having a plurality of restricted nail-receiving passages extending therethrough at the portion thereof exposed to the weather when applied, the portions of said board adjacent each exposed surface thereof and around each passage being saturated with waterproof material, the saturated portions around adjacent passages being spaced apart a distance much greater than their area whereby the major portion of the board is unsaturated and a masonry-simulating coating covering the exposed face of said board.

9. A construction member comprising a rigid composition board having a plurality of nail-receiving passages extending therethrough, and waterproof material applied to the exposed surfaces of the board and to the walls of said passages, at least the portions of said board around one end of said passages being saturated with said waterproof material to strengthen and rigidify the board adjacent the head of a nail received in the passage.

10. A building covering member comprising a composition board having a plurality of nail receiving passages extending therethrough at the portion thereof which is exposed to the weather when applied, said passages being of a diameter substantially equal to the thickness of a nail and a continuous masonry simulating waterproof plastic coating on one surface of said board, said coating extending into and filling the outer end of each passage.

11. A member as defined in claim 10, wherein said coating has portions simulating mortar joints and positioned over said passages, and said coating is indented in registration with each passage.
